UNITED STATES PATENT OFFICE.

CHRISTIAN A. JOHNSON AND HANS THISSENUS, OF LARAMIE, WYOMING.

SANDER.

1,089,224.

Specification of Letters Patent.

Patented Mar. 3, 1914.

Application filed November 29, 1913. Serial No. 803,819.

To all whom it may concern:

Be it known that we, CHRISTIAN A. JOHNSON and HANS THISSENUS, citizens of the United States, residing at Laramie, in the county of Albany and State of Wyoming, have invented new and useful Improvements in Sanders, of which the following is a specification.

This invention relates to sanders such as are used on locomotives for the purpose of sanding the track, the object of the present invention being to produce either a single or double sander embodying means for regulating the discharge of sand from the box and also preventing the sand from becoming congested and closing the discharge orifice or air passage of the nozzle or nozzles, whereby the sanding device as a whole is maintained in perfect working condition at all times.

With the above and other objects in view, the invention consists in the construction, combination and arrangement of parts, as will hereinafter be more fully described, illustrated and claimed.

In the accompanying drawings:—Figure 1 is a longitudinal section through a sander embodying the present invention. Fig. 2 is a detail perspective view of one of the nozzles. Fig. 3 is a detail perspective view of one of the sieves or screens.

Referring to the drawings 1 designates a sand box of any desired size provided in the opposite ends thereof with sand receiving openings 2 each of which is internally threaded as shown at 3 to receive a sand supply pipe (not shown).

In one side the box 1 is formed with an internally threaded opening 4 to receive the externally threaded cylindrical body portion 5 of an air nozzle 6, the outer end of said body being provided with a hexagonal face 7 to receive a wrench for the purpose of adjusting the nozzle in relation to a discharge opening 8 formed in the opposite side of the box from the nozzle receiving opening 4.

9 designates a lock nut which is threaded upon the body of the nozzle for the purpose of fixing the adjustment thereof after the proper adjustment has been obtained.

The discharge end of the nozzle is of ogee shape as clearly shown in Figs. 1 and 2 and the air passage 10 therein is of corresponding shape thereby tending to defeat

the backward movement of any particles of sand or foreign matter through the nozzle so as to clog the same. The nozzle is also centrally bored as shown at 11 and internally threaded as at 12 to receive a sieve or strainer 13. This strainer is externally threaded as at 14 and screwed into the internally threaded bore of the nozzle as clearly shown in Fig. 1 while the outer portion of the sieve is materially reduced in diameter as shown and formed with a large number of small perforations 15 through which the air from a suitable connection screwed into the outer end of the nozzle body 5 is received, the air then passing through a central bore 16 in the sieve and outward through the tortuous passage 10 extending lengthwise of the nozzle.

In Fig. 1 of the drawings we have shown what is termed a double sander or one that is provided with two nozzles for simultaneously discharging two streams of sand upon the rails. It will be understood, however, that a small sand box with a single discharge nozzle may be manufactured if so desired. The length of the sand box is such, as shown in Fig. 1, that the nozzle, notwithstanding the shape thereof, may be turned in order to adjust the distance between the discharge end of the nozzle and the exit opening 8 which receives the discharge pipe through which the sand is conducted to the rails. In this way the amount of discharge of sand may be regulated. The form of nozzle and air passage extending therethrough, taken in connection with the construction and arrangement of the sieve, checks the sand from working backwardly in the nozzle when the air is cut off and, by reason of the fact that the sieve is contained wholly within the body of the nozzle, the air pipe or connection may be screwed into the internally threaded bore of the nozzle without interfering with the sieve as will be readily understood by reference to Fig. 1.

The nozzle may be easily removed from the box 1 and the sieve may be removed from the nozzle for the purpose of cleaning out the passages both in the nozzle and the sieve, whenever required.

The sieve at its outer closed end is provided externally with a screw driver nick 17 to facilitate the insertion and removal of said sieve within the nozzle.

What we claim is:—

A sand box provided with a nozzle receiving opening in one side thereof and a sand discharge opening in the opposite side thereof, in combination with an air nozzle adjustably threaded in the first named opening, said nozzle being internally bored and threaded, and a sieve threaded in said bore and provided with a central longitudinal bore closed at one end, said sieve being formed with a number of perforations

through the side wall thereof leading into said central bore.

In testimony whereof we affix our signatures in presence of two witnesses.

CHRISTIAN A. JOHNSON.
HANS THISSENUS.
